SECTOR SCAN CONTROL FOR ANTENNA SYSTEMS

Maynard D. McFarlane, Cambridge, Mass., assignor, by mesne assignments, to the United States of America as represented by the Secretary of the Navy

Application September 25, 1944, Serial No. 555,703

10 Claims. (Cl. 318—282)

1

This invention relates to a means for causing a rotatable member to oscillate back and forth about a given point and more particularly to a means for causing a rotatable antenna such as that used in radio echo detection systems to scan a given and adjustable sector about a predetermined bearing point.

It is an object of this invention to provide a means for causing an antenna to scan about a given point with means for adjusting the angle of scan and the bearing point about which the scan occurs.

Other objects and features of the present invention will become apparent upon a careful consideration of the following detailed description when taken together with the accompanying drawings, the single figure of which represents a preferred embodiment of the invention.

The single figure of the drawings is an elevational view of an antenna scan control mechanism constructed in accordance with the principles of the invention, certain brace and support members for which are omitted here for purposes of simplifying the illustration.

In reference to the figure there is shown an antenna 10 or a "spinner" as it is sometimes known as, which is capable of scanning through 360° continuously. The antenna 10 is driven by a drive motor 11 which is adapted to cyclically rotate the antenna back and forth under control of a reversing switch 12 and an impulse relay 13 or in either direction continuously whenever switch 26 is opened. More specifically relay 13 and reversing switch 12 is of a type now known to the art which is arranged in a first position of contact, in which it is sustained until the relay receives a pulse of energization at which time the switch 12 assumes a second position of contact where it is again sustained until the next succeeding pulse of energy whereupon the switch is returned to its original position of contact. Arranged with the antenna 10 and adapted to rotate therewith on an axis in space quadrature thereto is a crank like extension 14 upon which is mounted a switch 15, which is adapted to control the operation of relay 13 and switch 12 whenever switch 26 is closed. Switch 15 is also of a type readily available in practice, adapted to be open circuited upon the application of pressure to a cam member 23 or other suitable means capable of controlling the contacts thereof. Leading from the relay 13 are a pair of wires 16 and 17 which connect to the switch 15 through a pair of corresponding collector rings 18 and 19 which are carried by the member 14 at point 20. To control

2

the operation of switch 15 and hence reversing switch 12 a cam member 21 is provided, suitably arranged in alignment with the axis of rotation of member 14 and upon which is disposed a tapered cam surface 22 adapted to engage the cam follower 23 of switch 15.

In operation, as the antenna 10 rotates, the crank like extension 14 and attached switch 15 likewise rotate about the cam member 21 so that as the cam follower 23 disengages the cam surface 22, from one side thereof, the relay 13 is energized by means of battery 25 so as to operate the reversing switch 12 thereby changing the phase of the driving current to the armature of motor 11 and hence reversing the direction of rotation of the antenna. Whereupon the cam follower 23 will subsequently disengage the cam surface 22 from the opposite side thereof thus again energizing the relay 13 and switch 12 to restore the original phase of the driving current to the armature of motor 11 and hence the original direction of rotation to antenna 10. It is thus seen that the angle of antenna scan depends upon the perimeter of the cam surface 22, which may be adjusted by moving the cam member 21 in a longitudinal direction, while the bearing point about which the scan occurs may be controlled by adjusting the angular disposition of the cam surface 22.

Although I have shown and described only certain and specific embodiments of the present invention I am fully aware of the many modifications possible thereof therefore this invention is not to be limited except insofar as is necessitated by the prior art and the spirit of the appended claims.

What is claimed is:

1. A means for causing a rotatable member to oscillate back and forth about a given point, comprising a driving motor, a relay operated reversing switch disposed in the armature circuit of said motor and adapted to control the direction of rotation of said motor, a cam member upon which is disposed a tapered cam surface, a second rotatable member arranged to rotate with the armature of said motor and upon which is mounted a second switch adapted to engage said cam member in such a manner as to operate said relay controlled reversing switch whenever said second switch disengages said cam surface.

2. In apparatus for causing a member to oscillate, means for controlling the angle of said oscillation and the midposition of said oscillation comprising a driving motor coupled to said member, means adapted to reverse the direction of rotation

of said motor, a cam member upon which is disposed a tapered cam surface, said cam member being adapted to be moved laterally and in rotation, a second member arranged to rotate with said first-mentioned member, and a follower mounted on said second member and adapted to engage said cam and cam surface, said follower being further adapted to control the operation of said motor reversing means.

3. Apparatus as in claim 2 said apparatus further comprising means for disabling said motor reversing means whereby said first-mentioned member is caused to rotate continuously in one direction.

4. In apparatus for causing a member to oscillate, means for controlling the angle of said oscillation comprising a driving motor coupled to said member, means adapted to reverse the direction of rotation of said motor, a cam member upon which is disposed an elongated, tapered cam surface, said cam member being adapted to be moved laterally and in rotation, a second member arranged to rotate with said first-mentioned member, and a follower mounted on said second member and adapted to engage said cam surface, said follower being further adapted to control the operation of said motor reversing means.

5. In apparatus for causing a member to oscillate, means for controlling the angle of said oscillation and the midposition of said oscillation comprising a driving motor coupled to said member, a relay operated switch adapted to reverse the direction of rotation of said motor, a cam member upon which is disposed a tapered cam surface, said cam member being adapted to be moved laterally and in rotation, a second member arranged to rotate with said first-mentioned member and a switch mounted on said second member and adapted to be operated by said cam surface, said switch being further adapted to control the operation of said relay operated switch.

6. Apparatus as in claim 5 said apparatus further comprising means for rendering said relay operated switch inoperative whereby said first-mentioned member is caused to rotate continuously in one direction.

7. In apparatus for causing a member to oscillate, means for controlling the angle of said oscillation and the midposition of said oscillation comprising a driving motor coupled to said member, a relay operated switch adapted to reverse the direction of rotation of said motor, a cam member upon which is disposed an elongated, tapered cam surface, said cam member being adapted to be moved laterally and in rotation, a second member arranged to rotate with said first-mentioned member and a switch mounted on said second member and adapted to be operated by said cam surface, said switch being connected to control the operation of said relay.

8. In apparatus for causing a member to oscillate, means for controlling the angle of said oscillation comprising a driving motor coupled to said member, means adapted to reverse the direction of rotation of said motor, an elongated, cylindrical cam member upon which is disposed a tapered cylindrical cam surface, said cam being adapted to be moved along the direction of the axis thereof and in rotation about said axis, a second member arranged to rotate with said first-mentioned member, and a follower mounted on said second member and adapted to engage said cam and said cam surface, said follower being further adapted to control the operation of said motor reversing means.

9. In apparatus for causing a member to oscillate, means for controlling the angle of said oscillation and the midposition of said oscillation comprising a driving motor coupled to said member, means adapted to reverse the direction of rotation of said motor, an elongated cylindrical cam member upon which is mounted a cylindrical cam surface, said cam surface being included within a first angle at a first position on the axis of said cam and within a second and greater angle at a second position on the axis of said cam, said cam being adapted to be moved along the direction of said axis and in rotation about said axis, a second member arranged to rotate with said first-mentioned member, and a follower mounted on said second member and adapted to engage said cam and said cam surface, said follower being further adapted to control the operation of said motor reversing means.

10. In apparatus for causing a member to oscillate, means for controlling the angle of said oscillation and the midposition of said oscillation comprising, a driving motor coupled to said member, a relay operated switch adapted to reverse the direction of rotation of said motor, an elongated cylindrical cam member upon which is mounted a cylindrical cam surface, said cam surface being included within a first angle at one point on the axis of said cam and within a second and greater angle at a second point on the axis of said cam, said cam being adapted to be moved in the direction of said axis and in rotation about said axis, a second member arranged to rotate with said first-mentioned member, and a switch mounted on said second member and adapted to be operated by said cam surface, said switch being further adapted to control the operation of said relay operated switch.
